UNITED STATES PATENT OFFICE.

JOHN D. KARLE, OF NEWARK, NEW JERSEY, ASSIGNOR TO THE SINGER MANUFACTURING COMPANY, A CORPORATION OF NEW JERSEY.

SEWING-MACHINE BRAIDER OR CORDER.

1,182,279.

Specification of Letters Patent.

Patented May 9, 1916.

Application filed August 2, 1913. Serial No. 782,629.

To all whom it may concern:

Be it known that I, JOHN D. KARLE, a citizen of the United States, residing at Newark, in the county of Essex and State of

5 New Jersey, have invented certain new and useful Improvements in Sewing-Machine Braiders or Corders, of which the following is a specification, reference being had therein to the accompanying drawings.

10 This invention has for its object to insure precision in the presentation to the stitch-forming mechanism of a sewing machine of braids or substantially flattened cords of that class having a ribbed face with an intermediate groove in which the fastening 15 stitches are to be laid.

The invention consists in a carrier of suitable form provided with a thin guiding rib adapted to enter the groove or crease 20 in the braid and with guard flanges upon opposite sides thereof to securely house the braid and prevent its displacement from operative relation with the guiding rib. In a modified form of the device, the laterally 25 spaced guard-flanges form the integral side walls of a channel having an intermediate slot entered by the guiding rib which is mounted upon a separate spring-arm secured to the carrier.

30 In the accompanying drawings, Figure 1 is a perspective view representing a sewing machine throat-plate provided with the present improvement, and representing a section of material upon the lower face of 35 which a braid is being secured. Fig. 2 is a perspective view of the under side of the attachment, and Fig. 3 a perspective view of the carrier for the guiding elements detached from the base-plate. Fig. 4 is a perspective view of the carrier with guiding 40 elements of an alternative form, and Figs. 5 and 6 similar views of the separate parts thereof.

Referring to Figs. 1, 2 and 3, the throat-plate 1 is provided with the usual feed-dog 45 apertures 2 with extension 3 which is in practice formed with the usual needle-hole entered by the needle 4 in performing the stitching operation.

50 The attachment base 5 is of segmental form and provided upon its under face at the extremities with the fastening hooks 6 adapted to engage the straight edged margin of the throat-plate and intermediate its 55 extremities with the integral stud-pin 7

which in practice enters an aperture in the throat-plate to properly locate the attachment in a manner well known.

The base member 5 is formed with integral rivets 8 entering apertures 9 in the shank 10 of the carrier-arm 11 which is provided with a forwardly projecting extension 12 having the central depending guiding rib 13 and the laterally spaced guard-flanges 14 embracing the same and disposed wholly in front of the needle-aperture of the throat-plate. The guard-flanges 14 are somewhat deeper than the central rib and the carrier is sustained with the edges of such flanges resting upon the face of the throat-plate. The shank 10 is arched slightly adjacent the member 11 to form a guide-loop 15 beneath which the ribbed cord or braid *a* is led to the housing channel containing the guide-rib 13 which latter has an operative edge which is preferably wedge-shaped in cross-section, as represented in the drawings, but which is in any case sufficiently thin to enter the groove or crease in the upper face of the braid. 80 In the modification represented in Figs. 4, 5 and 6, the carrier is constructed substantially in accordance with that of the preceding figures, excepting that the top of the channel bounded by the guard-flanges 14 is provided with a slot 16 through which projects the depending guide-rib 13' at the outer end of the spring-arm 17 secured upon the carrier member 11 by means of the rivet 18. In both forms of the attachment, the carrier is sufficiently resilient to enable the guiding elements to yield in accommodating it to irregularities in thickness of the braid or cord; but by providing a yielding support for the guide-rib 13' this element is 85 adapted to rise and fall with variations in the depth of the groove in the braid or cord while permitting the edges of the guard-flanges to remain seated upon the throat-plate for insuring the proper confinement 90 of the braid or cord in proper register with the guiding rib.

100 In the operation of the attachment the guiding rib, which extends preferably slightly below the normal bottom of the groove in the braid, maintains a slight pressure thereon by reason of its slight distortion and its elasticity, so that the braid is accurately guided across the path of the needle to cause the stitches *s* to be substan- 105 110

tially concealed in such crease. This pressure of the guide-rib upon the braid also tends to prevent any turning of the latter upon edge in rounding abrupt bends in an ornamental pattern, such as that represented in dotted lines Fig. 1.

The spring-arm 17 is shown provided at one edge with a thumb-nail projection 19 by means of which the operator may raise it to 10 retract the guide-rib 13' out of operative position so as to accommodate ordinary smooth-faced flat braid or braids of other form than that represented in Figs. 1 and 3.

While the attachment is shown herein 15 constructed with fastening means whereby it is secured to the throat-plate, it is evidently immaterial to the present invention to what particular part of the work-support its securing means may be directly applied, as the sewing machine bed-plate or the bed-plate slide would obviously serve equally 20 well as a support therefor, so long as the braid-guiding element is properly positioned relatively to the stitch-forming mechanism and the work.

Having thus set forth the nature of the invention, what I claim herein is:—

1. A sewing machine braider comprising 30 a yielding arm provided at one end with a braid-guiding rib having a thin operative edge to enter a crease in the braid and guard-flanges upon opposite sides thereof and at the other end with means for securing it to a sewing machine work-support.

2. A sewing machine braider comprising

a yielding sheet metal carrying arm provided at one end with a guiding rib having a thin operative edge to enter a crease in the braid and with guard-flanges of greater depth embracing and spaced from said rib 40 and at the opposite end with means below the level of said guard-flanges for securing it to a sewing machine work-support.

3. A sewing machine braider comprising a carrier formed with a braid-channel and a 45 spring-arm overlying said carrier and provided with a guide-rib adapted to enter said channel for engagement of one style of braid, means being provided whereby said guide-rib may be maintained retracted from 50 said channel for other styles of braid.

4. In combination with a sewing machine work-support provided with a needle-aperture, a braider comprising a carrier having means for securing it to the work-support 55 and provided with a braid-guiding rib having a thin operative edge to enter a crease in the braid and directed toward said needle-aperture and guard flanges upon opposite sides of and normally connected with 60 and having a fixed spacing from said rib and disposed wholly in front of the needle-aperture.

In testimony whereof I have signed my name to this specification, in the presence of 65 two subscribing witnesses.

JOHN D. KARLE.
